UNITED STATES PATENT OFFICE.

WELCOME F. SWEET, OF ST. LOUIS, MISSOURI.

BLOAT-NEEDLE.

1,083,567.

Specification of Letters Patent.

Patented Jan. 6, 1914.

Application filed February 27, 1911. Serial No. 611,129.

To all whom it may concern:

Be it known that I, WELCOME F. SWEET, a citizen of the United States, residing at St. Louis, Missouri, have invented a certain 5 new and useful Improvement in Bloat-Needles, of which the following is a full, clear, and exact description, such as will enable others skilled in the art to which it appertains to make and use the same, reference being had to the accompanying drawings, forming part of this specification, in 10 which—

Figure 1 is a perspective view of a portion of an animal, and illustrating the use of my 15 improved bloat needle thereon. Fig. 2 is a perspective view of the preferred form of the needle. Fig. 3 is a front elevation of the point of the needle. Fig. 4 is a side elevation of the point of the needle.

20 My invention relates generally to surgical instruments, and more particularly to an instrument to be used by veterinarians and others for the relief of bloat in cattle and other animals.

25 The ailment commonly known as bloat is frequently met with in animals, particularly cattle, which ailment is a result of the formation of gas in the stomach, resulting from over-eating, particularly of green food, and 30 where bloat occurs it must be relieved quickly in order to avert the death of the afflicted animal.

It is the purpose of my invention to provide a simple, inexpensive device in the form 35 of a tubular needle which may be readily inserted through the skin of the animal and into the stomach, thereby permitting the gas to escape and thus relieve the bloated animal.

40 My invention consists in a short metal tube, one end of which is cut off at an acute angle so as to form a point having a pair of gradually curved cutting edges which will readily cut through the skin and flesh of 45 the animal in such a manner as to leave a wound having clean cut edges when the instrument is withdrawn.

To the above purpose, my invention consists in certain novel features or construction hereinafter described and claimed.

In the construction of the preferred form of my improved device, I make use of a small tube 1 preferably of metal, approximately 4 or 5 inches long, and provided on one end with a head 2 which is engaged when 55 the needle is forced into the stomach of the animal, and which prevents the needle from being wholly forced beneath the skin.

A sharp edged point 3 is formed on the forward end of the needle by cutting off said 60 end on an acute angle and by such formation, a pair of gradually diverging cutting edges 4 are formed which extend upward or rearward from the point until the diametrical center of the tube is reached and from 65 such point the edges gradually approach one another until they meet at the rear end of the face formed by the cutting off of the end of the tube.

When the point of the needle so constructed is forced into and through the skin, a semi-circular cut is formed by the cutting edges, and as said cutting edges are sharp, the wound made by the cut through the skin has clean cut edges, and will therefore heal 70 more readily than where the edges of the wound are torn and ragged. After the point of the needle has been inserted through the skin of the animal, pressure is applied to the head to force the needle the full length into 75 the animal and as the point is forced into the stomach, the gas therein will find exit 80 the animal and as the point is forced into the tubular needle, thereby relieving the animal.

A bloat needle of my improved construction is comparatively simple, can be manufactured at little cost, and by cutting the forward end of the needle off at an acute angle, a sharp point and a pair of gradually diverging cutting edges are formed which 85 permits the needle to be readily inserted through the animal's skin and flesh, and the wound formed by the insertion of the needle has clean cut edges which will readily heal 90 without injurious after effects. 95

I claim—

The herein described bloat needle comprising a metal tube having a smooth unbroken exterior surface throughout its length, one end of which tube is cut off at 100

an acute angle relative to the axis of said tube to form an entering point, a portion of the tube adjacent to said point being flattened to form a blade, the width of which is greater than the diameter of the tube, and a head on the opposite end of the needle.

5 In testimony whereof I hereunto affix my

signature in the presence of two witnesses, this 21st day of February, 1911.

WELCOME F. SWEET.

Witnesses:

M. P. SMITH,
B. S. REID.
